US00D849870S

(12) **United States Design Patent** (10) Patent No.: **US D849,870 S**
Cluff et al. (45) Date of Patent: **** May 28, 2019**

(54) **BUMPER FOR GUN**

(71) Applicants: **Matthew Roy Cluff**, Kanab, UT (US);
Alan Dugger, Leander, TX (US);
Kenneth D. Lewis, St. George, UT (US)

(72) Inventors: **Matthew Roy Cluff**, Kanab, UT (US);
Alan Dugger, Leander, TX (US);
Kenneth D. Lewis, St. George, UT (US)

(**) Term: **15 Years**

(21) Appl. No.: **29/634,335**

(22) Filed: **Jan. 19, 2018**

(51) LOC (11) Cl. **22-01**

(52) U.S. Cl.

USPC **D22/108**

(57) **CLAIM**

The ornamental design for a bumper for gun, as shown and described.

DESCRIPTION

FIG. 1 is a perspective view of the bumper for gun;
FIG. 2 is a left side elevation view of the bumper for gun;
FIG. 3 is a front elevation view of the bumper for gun;
FIG. 4 is a top plan view of the bumper for gun; and,
FIG. 5 is a bottom plan view of the bumper for gun.
The right side elevation view is a mirror image of the left side elevation view; and
The back elevation view is a mirror image of the front elevation view.

1 Claim, 4 Drawing Sheets
